UNITED STATES PATENT OFFICE.

LEON GREENFIELD, OF NEW YORK, N. Y.

ANATOMICAL BRIDGE-ARTICULATOR.

1,353,039.

Specification of Letters Patent. Patented Sept. 14, 1920.

Application filed March 12, 1920. Serial No. 365,262.

To all whom it may concern:

Be it known that I, LEON GREENFIELD, a citizen of the United States, residing at New York, in the county of New York and 5 State of New York, have invented new and useful Improvements in Anatomical Bridge-Articulators, of which the following is a specification.

This invention relates to anatomical devices used in the practice of dentistry, and more particularly it relates to articulators.

Some of the objects of the invention are: to produce a device of the character mentioned which is comparatively inexpensive; 15 one which is reliably effectual; one which is simple of construction and with which any dentist may perform a piece of work successfully since the device by reason of its construction may be manipulated to obtain 20 the precise and proper occlusion which thus permits and leads up to the obtainment of ultimate proper articulation with false teeth in the mouth of an individual by such individual.

25 In the drawing forming a part of this specification:

Figure 1 is a perspective view of the device.

30 Fig. 2 is a central longitudinal sectional view.

Referring now to the drawing, it will be seen, that the device consists of a pair of members 10 and 11 both of which are supported for movement by the member 12. 35 The member 12 is U-shaped to provide a horizontally disposed connecting portion 12 and sides 14 which are disposed in parallelism in spaced relation. The member 10 is made up from a single piece of material. 40 The member 10 has an opening 15 therein, and the side edges thereof converge toward the reduced extension 16. The extension 16 is provided with pintles 17 which are received in alining apertures 18 in the sides 45 14. Some of the material from which the member 10 is made, is bent and formed to provide a stop 19 and a flexible or spring-like extension 20 which is disposed to contact with the portion 13 of the member 12.

50 The extension 20 permits of the movement of the member 10 within a certain arc. The extreme end of the extension 16 by coming into engagement with the extension 20, which is in engagement with the portion 13, 55 limits the upward movement of the member 10, whereas, the extension 20 and the

extension 16, in the movement of the member 10 downwardly, come together and engage the portion 13 thus limiting the downward movement of the member 10. The member 10 is bent as at 21 and rebent as at 22 for a purpose to appear.

The member 11 is made similarly to the member 10, as to material and shape, but it is not provided with the stop 19 and the extension 20 forming a part of the member 10. The member 11 has an opening 23 therein and a reduced extension 24. The extension 24 is provided with pintles 25 which are received in alining apertures 26 in the sides 14. An adjusting screw 27 is carried by the member 11 and co-acts with the stop 19, such feature together with the fact that the U-shaped member 13, and the member 11 carried thereby, may be moved upon the pintles 25 permits the obtainment of the proper occlusion in particular cases. The member 11 is bent as at 28, and rebent as at 29. This latter feature of construction which, as is known, is also true of the other member 10 give the desired spread or pitch between the major tooth plate or bridge supporting portions of the members 10 and 11 and at the same time give an approximate average anatomization. By 85 adjustment of the screw 27, which as stated co-acts with the stop 19, and by shifting the member 11 and its supporting member 13, the precise and proper occlusion may be derived for the obtainment of the ultimate 90 particularly desired articulation.

What is claimed as new is:—

1. An anatomical articulator embodying a plurality of movable members, means including a spring-like extension carried by 95 one of said members, a portion of said extension being in yielding contact with another of said members for yieldingly allowing two of said members to have a relative compound movement.

2. An anatomical articulator including pivotally mounted members having supporting portions, a support for the members, means including a spring-like extension carried by one of said members, a portion of said extension being in yielding contact with the support for allowing said pivoted members to have a relative compound movement, laterally, longitudinally and vertically. 105

3. An anatomical articulator, embodying a plurality of movable members, means in-

100

110

- cluding a spring-like extension carried by one of said members, a portion of said extension being in yielding contact with another of said members for yieldingly allowing two of said members to have a relative compound movement, laterally, longitudinally and vertically; and means for varying the distance of vertical movement of said members.
- 10 4. An anatomical articulator including a pair of pivoted members, an extension embodied by one of said members, said extension embodying a yieldable portion and a portion constituting a stop, a support for said members, the yieldable portion being in contact with said support for allowing the pivoted members to yield when closed to the limit, and an adjusting means which coacts with said stop for varying the distance of movement of said members toward each other.
- 15 5. An anatomical articulator including pivoted members, a spring-like extension integral with one of said members, a support for said members with which support said extension is in yielding contact; the pivoted members having a relative compound movement including the movement of one of said members toward and away from the

other member, and means for varying the distance of movement of one member toward the other member.

6. An anatomical articulator including a pair of pivoted members having supporting portions and being movable toward and away from each other, a support for said members, means carried by one of said members adapted to coact with said support for yieldingly supporting one of said members, and means including a coacting screw and stop for limiting the movement of one of said members toward the other member and for obtaining varying spreads between said supporting portions.

7. An anatomical articulator including a pair of members having universal relative movement, and means for permitting said movement of said members including a supporting member to which said members are pivoted, a spring-like extension integral with one of said members engageable with said support, a stop on one of said members and an adjusting means carried by the other member.

In testimony whereof I have affixed my signature.

LEON GREENFIELD.
